UNITED STATES PATENT OFFICE.

HENRY H. NORRINGTON, OF WEST BAY CITY, MICHIGAN.

MANIFOLDING-BOOK.

SPECIFICATION forming part of Letters Patent No. 768,948, dated August 30, 1904.

Application filed June 15, 1903. Serial No. 161,524. (No model.)

To all whom it may concern:

Be it known that I, HENRY H. NORRINGTON, a citizen of the United States, residing at West Bay City, county of Bay, State of Michigan, have invented a certain new and useful Improvement in Manifolding-Books, of which the following is a specification, reference being had to the accompanying drawings, which form a part of this specification.

10 My invention has for its object certain new and useful improvements in a manifolding-book or analogous device; and it consists of the construction hereinafter described and claimed, and illustrated in the accompanying drawings, in which—

Figure 1 is a view in perspective illustrating my invention. Fig. 2 is a view in elevation, showing one of the pages folded over a carbon-sheet. Fig. 3 is a similar view showing two pages folded over the carbon-sheet. Fig. 4 is a detail view of one face of one of the pages of the book. Fig. 5 is a view in perspective, showing two pages of the book loosely folded in position for use.

25 The object of my invention is to provide a manifolding-book or sales order-book or a book for analogous purposes employing a double-faced carbon-sheet whereby manifold copies of an order or receipt or analogous 30 matter may be made.

For certain purposes, as in shipping railway freight, for example, it is desirable to have a receipt or bill to follow the goods or to be given to the sender and another duplicate copy to be kept by the agent and another triplicate copy to be kept in permanent form.

My invention is designed to provide a manifolding-book or sales order-book or book for analogous purposes provided with three pages or sections forming one leaf normally of the book, the sections being separated by perforated lines, one section or page of each leaf being permanently bound to constitute a book, the bound pages or sections all being retained in permanent engagement with the cover portion after all the other sections or pages have been removed, so that the bound sections or pages can readily be kept in permanent form for reference.

I carry out my invention as follows:

In the drawings, *a* represents a completed book, said book comprising a base or cover portion *b* and a plurality of leaves *c*. Each of the leaves is formed with outside or lateral sections *d*, *e*, and *f*, all of the sections or pages *d*, and with folding sections being bound as at the upper edge of said sections *d* in any suitable manner—as, for example, by staples *g*—whereby the sections *d* are permanently bound upon the cover or base *b*. I do not limit myself to any particular way of binding the sections *d* together upon the base or cover portion. The page or section *f* is at the opposite end of the leaf from the page *d*. The intervening page *e* constitutes the original or the section upon which the original copy is to be made. The sections *d* *e* are formed with perforations therebetween, as indicated on the lines *h* *h*. The pages *e* *f* are formed with intervening perforations, (indicated on the line *i* *i*.) A double-faced carbon-sheet is indicated at *j*, the same being secured at one end thereof in any suitable manner in the book, as upon the lower cover portion *b*, as shown, or it might be secured to one of the leaves of the book. The carbon-sheet is of a length sufficient to normally extend over the sections or pages *d* *e*. When the carbon-sheet is so in place upon the pages *d* *e*, the page *f* is folded over thereupon on the perforated line *i* *i*, after which the pages *e* *f* are further folded over upon the page *d* upon the perforated lines *h* *h*. The book is then ready to receive the matter. It will be seen that the lower surface of the page *e* is thus uppermost to receive the original impression or writing upon its under surface, which has now been folded over to bring the lower face of the page uppermost. It will be obvious that duplicate carbon impressions are at the same time with the original impressions made upon the pages *d* *f*. The pages *e* *f* are then unfolded, permitting the ready removal of the page *f* by tearing it off along the line *i* *i*. By throwing back the carbon-paper the page *e* may readily be separated from the page *d* along the line *h* *h*. The page *d*, which has just received an impression, is then thrown back or folded over along its bound edge, permitting

the carbon-paper to be replaced over the underlying pages *d e* ready for an additional record to be made. It will be obvious that the pages *d* are never removed from the book.

5 The binding of the pages or sections *d* along the upper edge thereof renders it desirable to make the pages *e f* shorter than the pages *d*—that is, the pages *d* project at their upper ends upward and beyond the upper edges of the 10 pages *e f*. This greatly facilitates manipulation of the carbon-sheet.

Any suitable printed matter may of course be printed upon the pages *d e*, and *f*, the page *e* bearing the printed matter on the reverse side from the printed matter upon the pages *d f*. The separated pages *e* and *f* may readily be utilized as above described or in any desired manner, while upon the bound pages *d* a permanent record is made for safe 15 keeping. When all of the sections or pages *e* and *f* of a given book have been separated from the pages *d*, the lower cover or base portion *b* may be readily cut off on a line corresponding to the perforated lines *h h*.

I do not limit myself to binding the carbon-sheet in a book, as a loose carbon-sheet might be utilized; but it is obviously of advantage to have the carbon-sheet permanently attached to the book in any suitable manner.

What I claim as my invention is—

A manifolding-book of the nature described formed of a plurality of leaves, each leaf divided into a permanent section and a plurality of folding sections by weakened lines, the permanent sections of the leaves being bound together at their upper edges, the folding sections of each leaf arranged to fold over the permanent section, the outer lateral edges of the permanent sections being free for the insertion of a carbon-sheet therebetween.

In testimony whereof I have signed this specification in the presence of two subscribing witnesses.

HENRY H. NORRINGTON.
